(57) CLAIM

The ornamental design for the toilet stool foot rest, as shown and described.

DESCRIPTION

FIG. 1 is a perspective view of a toilet stool foot rest; FIG. 2 is a left side view of the toilet stool, illustrating the foot rest that is in uniform broken lines; FIG. 3 is a right side elevation view of the toilet stool foot rest; FIG. 4 is a front side elevation view thereof; FIG. 5 is a rear side elevation view thereof; FIG. 6 is a top plan view thereof; FIG. 7 is a bottom plan view thereof; FIG. 8 is a cross sectional view along line 8-8 of FIG. 4; and, FIG. 9 is a cross sectional view along line 9-9 of FIG. 4. The uniform broken lines in the drawings depict portions of the toilet stool foot rest that form no part of the claimed design.
